PACKING FOR HOMOGENIZERS

John A. Clark, St. Johnsbury, Vt., assignor to
 Manton-Gaulin Manufacturing Company, Inc.,
 St. Johnsbury, Vt., a corporation of Vermont

Application September 28, 1933, Serial No. 691,339

1 Claim. (Cl. 286—35)

This invention relates to homogenizers used extensively by dairies for treating milk and cream.

It has been common practice to clean and sterilize such apparatus periodically, usually at the beginning or end of the day's run. In fact, it frequently is necessary to clean and sterilize the apparatus more often if the bacteria count of the product is running abnormally high. Even with such painstaking care it has been impossible for dairymen to maintain the bacteria count of the product as low as desired. This is due in part, at least, to the fact that the operative parts of the apparatus have been accessible only with great difficulty. Consequently, it has been difficult to clean and thoroughly sterilize the apparatus. These difficulties have been overcome to a large extent by the construction described in my co-pending application Serial No. 504,322, filed December 23, 1930, wherein the intake manifold and intake valves are easily removable.

The product to be treated is supplied to the compression cylinder of the homogenizer where it is subjected to high pressure by a plunger reciprocated in the cylinder by an external force. The stuffing box surrounding the plunger cannot be removed from the apparatus without substantially completely dismantling the apparatus. Consequently, it has been impossible to clean and sterilize the stuffing box and the packing therein. This stuffing box, therefore, has been a constant source of bacteria formation which could not be overcome because the stuffing box could not be removed and sterilized.

It is an object of the present invention to overcome this difficulty by the provision of a stuffing box so constructed that it may be thoroughly cleaned and sterilized.

The invention will be more clearly understood from the following description in conjunction with the accompanying drawing: in which,

Fig. 1 is an elevational view, partly in section, of a portion of an apparatus embodying the invention; and

Fig. 2 is a detail sectional view of a portion of the apparatus.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

An homogenizer embodying the invention is illustrated in the accompanying drawing and comprises a casing 10 having a cylinder block 11

provided with a bore or cylinder 12. A plunger 13 extends into the bore 12 and is reciprocable therein. The outer end of the plunger 15 is suitably connected to a cross head 16 reciprocated through a connecting rod 17 connected to a revolving crank (not shown). The casing 10 is provided with a chamber 18 adjacent the outer end of the bore 12 and is accessible through an opening normally closed by a detachable cover 19.

The outer end of the bore 12 is provided with a threaded enlargement 22 adapted to receive the outer threaded sleeve 23 of a stuffing box which surrounds the plunger 15. The inner end of the sleeve 23 is provided with a circular groove 24 adapted to receive a packing ring 25 for effecting a fluid-tight joint between the sleeve 23 and the cylinder block 11. A plurality of flexible or compressible packing rings 30 are interposed between the sleeve 23 and the plunger 15. A solid packing ring 32 is interposed between the packing rings 30 and the cylinder block 11. A solid packing ring 32 is interposed between the packing rings 30 and the inner end of an inner adjustable sleeve 33 having threaded engagement with the outer end of the outer sleeve 23.

If it is desired to clean and sterilize the stuffing box the outer sleeve 23 is removed from the threaded enlargement 22 of the bore 12 and is moved to the left, as viewed in Figure 1, along the plunger 15. The adjustable inner sleeve 33 is then adjusted to force the packing rings 30 out through the inner end of the outer sleeve 23 as shown in Figure 2. The stuffing box may then be thoroughly cleaned and sterilized. Preferably, the packing rings 30 are split, as shown at a 35 in Figure 2, so that they may be readily removed from the plunger 15 and thoroughly sterilized.

I claim:

In an apparatus having a stationary cylinder block provided with a bore having a threaded enlarged outer end and a reciprocable plunger extending into said bore, the combination therewith of a stuffing box surrounding said plunger comprising an outer sleeve threaded in said enlarged outer end of the cylinder and having an inner packing receiving chamber extending from its inner end to a point adjacent the outer end, the outer end portion of said sleeve being internally threaded, an adjustable inner sleeve of a length substantially equal to the length of the outer sleeve, said inner sleeve being externally threaded for engagement with the internally threaded portion of the outer sleeve and normally positioned substantially outside the packing receiving chamber, and packing rings normally positioned in said chamber and projectable along the plunger when the outer sleeve is removed from the cylinder block and the inner sleeve is threaded therethrough.

JOHN A. CLARK. 60
